JEAN-BAPTISTE VICTOR DALLEMAGNE, OF PARIS, FRANCE.

SPARK-EXTINGUISHER.

1,035,423.

Specification of Letters Patent. Patented Aug. 13, 1912.

Application filed February 27, 1911. Serial No. 611,253.

To all whom it may concern:

Be it known that I, JEAN-BAPTISTE VICTOR DALLEMAGNE, a citizen of the Republic of France, and resident of Paris, France, 5 have invented new and useful Improvements in Spark-Extinguishers, which improvements are fully set forth in the following specification.

This invention relates to an apparatus 10 adapted to be arranged in the interior of any chimney for the purpose of preventing sparks which are carried by the draft in the chimney, from escaping outside.

This spark extinguishing apparatus, 15 which is applicable to all furnaces, steam engines and chimneys, is more particularly intended for locomotives, portable boilers and marine boilers, the draft in which is produced by an injection of steam into the 20 chimney.

The extinguishing apparatus forming the subject of this invention is illustrated by way of example in the accompanying drawing showing its application to a locomotive.

At the bottom portion of the chimney *a* is secured a vertically disposed body *b* of cylindrical shape, opening at the top into the chimney *a*, and at the bottom into the 30 smoke box *c*. The body *b* is secured to the chimney by means of a frusto-conical part *d*. In the interior of the body *b* is arranged a hollow nozzle *e* suitably connected to the steam pipes *f* producing draft in the chimney. The hollow nozzle which is stationary 35 is surrounded by blades *h* connected together by vertical bands *i* forming a projection or offset. These blades which start from the bottom portion of the nozzle *e*, de-

scribe about the latter a helical line interrupted by the off-sets *i* and terminate at the upper portion, forming in the interior of the body *b* of the extinguisher a kind of helical path with a constant area, along 40 which must travel the sparks escaping from the furnace. The helical body or screw thus formed, is secured in any desired manner to the interior of the body *b* of the extinguisher, and to the nozzle *e*. The number 45 of blades *h* varies according to the dimensions given to them, and according to the height of the body of the extinguisher. The sparks coming from the furnace, impinge therefore against the first blade *h* 50 which cools them and then, if not extin-

guished after having passed the first projection *i*, they meet the second blade where they are extinguished. The sparks which, on contact with the first blades, are not extinguished, follow the helical path *h* provided between the blades *h* and the projections or off-sets *i*, where they become extinguished on contact with successive blades. The sparks or cinders are arrested by striking against the vertical walls *i*, and then fall 65 back on the blades *h* and follow the path *h* in the opposite direction and fall back into the ash pit.

When, as in the example illustrated, the extinguisher is applied to a locomotive, the 70 nozzle *e* in the helical body or screw constituted by the blades *h*, is hollow and connected, as already stated, to the steam pipes *f*. It is therefore possible to produce a draft in the chimney by injecting into the 75 chimney *a*, either quantities of steam, or a continuous jet, by means of the nozzle *e* which forms a conduit for injecting steam. A blowing pipe *m* is shown as extending through the tube sheet and discharging into 80 the stack, in a well-known manner, and this pipe may be used for creating a forced draft when the engine is not using steam. The same would be the case in a portable engine.

The spark extinguishing apparatus can 85 be made of any dimensions and of any suitable material. It can be arranged either at the bottom or at any point of the chimney, or in the smoke box.

This device economizes fuel and reduces 90 the choking of the smoke tubes, which results in an economy of labor for cleaning the said tubes.

Claims.

1. In a spark extinguishing device, the 95 combination with a vertically arranged conduit through which the products of combustion pass from the bottom upwardly, of a helically arranged spiral blade located within the conduit and substantially in contact with the walls thereof, said blade comprising smooth, cooling sections progressively offset from each other in the direction of the axis of the helix, said sections being connected by vertically disposed cinder arresting walls extending parallel with 100 said axis.

2. In a spark arresting device, the combination with a cylindrical conduit through 105 which the products of combustion pass, of 110

a centrally disposed member arranged there-
in and a helical blade located within said
conduit and extending from said centrally
disposed member to the wall of the conduit,
5 said blade comprising cooling sections pro-
gressively spaced apart in the direction of
the axis of the conduit, said sections being
connected by cinder arresting walls extending
radially from said centrally disposed

member and parallel with the axis of the 10
helix.

In testimony whereof I have signed this
specification in the presence of two sub-
scribing witnesses.
